UNITED STATES PATENT OFFICE.

RICHARD B. BROWNE, OF MASPETH, NEW YORK, ASSIGNOR TO RICHEY, BROWNE & DONALD, OF MASPETH, NEW YORK.

PROCESS FOR CASTING.

982,572.

Specification of Letters Patent. Patented Jan. 24, 1911.

No Drawing.

Application filed April 12, 1906. Serial No. 311,393.

To all whom it may concern:

Be it known that I, RICHARD B. BROWNE, a citizen of the United States, residing at Maspeth, in the borough of Queens and 5 State of New York, have invented a new and useful Improvement in Processes for Casting, of which the following is a specification.

The invention relates to a process for 10 producing or casting copies of models.

It is especially adapted for the artistic reproduction of the original modeling in the fine arts, or in the decorative arts, where the original model is in more or less high 15 relief and undercut. The improvements may, however, if deemed desirable, be applied to the ordinary run of commercial foundry work regardless of the depth of the mold or the presence or absence of undercut 20 features.

For the purpose of illustrating one practical application of the invention to the art of metal founding, it will be assumed that the original model to be reproduced is in 25 alto-relievo, or high relief, with deep and numerous undercut portions, the lines of which extend at various angles and curves.

In reproducing by casting the above model in iron, bronze, or the like, a soft plastic 30 negative mold (say a glue mold) is first made, from which, upon solidifying, the model can be drawn intact from the undercut parts of the mold owing to its elasticity. Into this negative mold is then placed a 35 friable composition, preferably in a wet state, which forms the pattern. After this pattern composition has set the elastic negative mold is drawn away from the pattern. It generally stands a day or two to dry. After 40 the pattern is removed from the elastic mold, it is coated with a few coats of shellac, or other similar substance, for the purpose of surface hardening the pattern, and also for preventing any oil which may be in the 45 molding sand from impregnating the pattern composition. The pattern thus formed may be used for any purpose or in any connection for which it may be found suitable. The pattern is, for example, peculiarly applicable for use in sand or molded mold work, particularly baked sand molds, which generally have combined therewith a binding agent, such as oil. In such cases the friable pattern is molded in the sand in the

usual way, and the mold with the pattern 55 therein is put in a baking oven. The heat bakes and effects the hardening of the mold after the usual practice, and at the same time increases the friability of the composition of the pattern. 60

After the mold is baked an air current or other agent is applied to the pattern, which blows away the friable pattern in the form of small particles and dust, whereupon the baked mold is ready for use for casting the 65 destroyed pattern in molten metal.

The mold thus formed is not only capable of use in metal founding, but in other kinds of casting or molding with plastic materials having the properties of setting or hardening in molds. 70

The material of which the pattern composition is formed is essentially a pulverable friable substance, preferably mixed with water. It has practically no, or very slight, 75 tenacious quality, sufficient only to enable it to hold its shape when molded. It is peculiarly susceptible after drying to disintegration, a slight molecular or mechanical disturbance, such, for example, as an air current, causing it to crumble and blow away. In other words, the pattern mixture is rotten and incapable of maintaining its molded form as a pattern when exposed to slight disturbances. 80

The rotten pattern composition may be made of any substance or combination of substances which will have the characteristics above mentioned. For example, one composition having the above features can 90 be made of about equal parts of powdered pumice stone and plaster of paris mixed with water, to which may be added alum or alum-water. This composition in its wet state is not only friable, rotten and without 95 material tenacious quality, but after being dried or baked is rendered still more friable.

After having been molded and set the exterior surface of the pattern is painted or coated, (say with a few coats of shellac) 100 in order to relatively harden the surface. The coating of the pattern permits it to be handled during the molding operations and also prevents any oily matter which may be incorporated in the molding sand from permeating the pattern and locally altering its degree of friability. 105

Duplicates of the original molding may,

of course, be made in the elastic negative mold.

What I claim is:

- 5 1. A foundry process which consists in making a friable pattern, then hardening the surface thereof, then making a mold from the pattern, and thereafter disintegrating the pattern before removing it from the mold.
- 10 2. A foundry process which consists in making a friable pattern, then making a mold from the pattern, and then increasing the friability of the pattern when in the mold.
- 15 3. A foundry process consisting in forming a pattern of friable composition, then hardening the surface thereof, then forming a mold from the pattern, and finally baking the mold and pattern.
- 20 4. A foundry process which consists in molding a friable pattern and baking the mold and pattern together.
- 25 5. A foundry process which consists in making a friable pattern then coating the same, then making a mold of the pattern, and finally baking the mold and pattern together.
- 30 6. A foundry process consisting in forming a pattern, making a mold upon the pattern, baking the mold and pattern to in-

crease the friability of the latter, and finally crumbling away the pattern from the mold.

7. The herein described process which consists in making elastic molds of the model to be copied, then making in a friable composition a duplicate of the model from the elastic mold, then molding the friable duplicate, and finally removing or blowing away the friable composition duplicate from the mold.

8. A process consisting in making a friable pattern; molding the pattern and then breaking up the pattern and removing it from the mold.

9. A process which consists of making a friable pattern, forming a mold on the pattern and then disintegrating the pattern leaving the mold ready for casting.

10. A process which consists of making a friable pattern, forming a mold on the pattern and then disintegrating the pattern within the mold and removing the fragments of the pattern leaving the mold ready for casting.

In testimony whereof I have affixed my signature in the presence of two witnesses.

RICHARD B. BROWNE.

Witnesses:

J. D. HOGG,
F. ARUNDEL.
